UNITED STATES PATENT OFFICE.

LUIGI OLIVERO, OF GENOA, ITALY.

CAR-COUPING.

1,163,447.

Specification of Letters Patent.

Patented Dec. 7, 1915.

Application filed December 22, 1914. Serial No. 878,592.

To all whom it may concern:

Be it known that I, LUIGI OLIVERO, mechanical engineer, a subject of the King of Italy, residing at Genoa, Italy, have invented 5 a useful Improvement in Car-Couplings, of which the following is a specification.

This invention relates to the mechanisms for the automatic coupling of cars, essentially formed of two jaws each of them rotating around a journal, and of a link adapted to remain engaged between said jaws by reason of the impact or pressure of the latter against the former, as well as for the interposition, at the right moment, of a convenient locking member.

According to present invention the above stated rotating jaws are so constructed to remain open on the part designed to receive the shock of the link and shut on the part 20 where the interposition of the locking member is taking place.

By drawing two cars one near to the other, the link carried by one of them actuates the jaws of the other car so as to be drawn together and closed on the part of the said link, while they will open themselves on the opposite part and in this position will get locked by reason of the interposition, in the latter, of a locking member.

30 The link is entirely embraced by the jaws, just like a pin connecting rod in its bearing, whereby the coupling is effected.

The locking member is independent from the jaws and exercises its function at the 35 right moment, under the influence, for example of a weight lever, when, under the action of the link, said jaws will open themselves on its side, under the action, too, of said weight lever placed in a convenient position.

The accompanying drawings illustrate, by way of example, one construction of the invention.

In these drawings: Figure 1 shows a longitudinal vertical section of the coupling mechanism in locked position; Fig. 2, is a similar view showing the device in the position while the coupling is taking place; Fig. 3 shows a side elevation partly in section of 50 the link which forms one of the parts of the coupling device; Fig. 4 shows a plan view of the arrangement of the pair of coupling mechanisms at the end of the cars;

Fig. 5 shows a plan view of the mechanism 55 illustrated in Fig. 2.

Throughout these various figures, like numerals indicate corresponding parts.

In these, 1 indicates the drawbar of the jaws 4 and 5, and 2 is the link which remains engaged between them. On the drawbar 1 60 are firmly secured the two spaced walls 3 between which said jaws are located, said jaws being pivoted upon the journals 6. The junction of the two walls over the bar 1 is realized by means of bolts 7 and they 65 are kept at the required distance one from the other by band rings 7 placed around said bolts. On the side of the link the walls 3 are connected, by means of a part of the bolts 7 themselves, to a cup 8 possessing 70 ears 9. This cup has the object of guiding the link to the center of the jaws 4 and 5. This opportunity is offered in the case of the co-existence of the usual hand coupling mechanism, as well as with the coupling 75 object of the present invention.

By drawing two cars one near to the other the link 2 guided by the cup 8 will strike or press against the center of the two jaws, thereby causing their opening on the side of 80 the locking member 10. This latter guided by the walls 3 is controlled by the angle levers 11—12—13, and this one, in turn, by the forked connecting rod 14 operated by the lever 15, running loose on the shaft 18 85 controlled by the notched sleeve 24 keyed on the shaft 18, and this latter controlled by the lever 20 under the action of a weight or spring 27 guided along the rod 21 or by means of another convenient arrangement. 90

When the lever 19 driven by the spring 27 is in the position as represented in Fig. 2, the locking member 10 will press against the jaws, and as soon as these, by reason of the impulsion or shock of the link, have 95 opened themselves to a certain extent, the aforesaid locking member will then insert itself between them causing them to get locked in the position as shown in Fig. 1, whereby the coupling is effected.

When it is required to uncouple the cars it is only necessary to bring the lever 19, by means of lever 20, in the position as shown in Fig. 2, thus enabling the sleeve 24, 24 which rotates with the lever itself, 105 to press with its notch against the notch

of lever 15, thereby exercising an action upon the angle lever 11—12—13 by means of the connecting rod 14, whereby the locking member 10 will be drawn back causing it to remain outside of the jaws.

In order to cause the link to remain in the horizontal position there is a regulated compressed spring (Fig. 3).

Since the locking member (10) controlling device is arranged below the drawbar 1, it therefore offers, at equal conditions, more warranty of working since the weight of the various parts contributes to keep the mechanism shut.

Having now particularly described and ascertained the nature of my said invention and in what manner the same is to be performed, I declare that what I claim is:

1. A car coupling of the character described comprising in combination jaws pivoted intermediate their ends for movement in a vertical plane, the pivoted axis of the upper jaw being situated forward of the center of gravity thereof, and the pivotal axis of the lower jaw being located to the rear of the center of gravity thereof.

2. In a car coupling of the character de-

scribed, the combination of two jaws, bearings upon which the jaws pivot, the pivoted axis of the upper jaw being situated forward of the center of gravity thereof and the pivoted axis of the lower jaw being located to the rear of the center of gravity thereof, a link carried by one of the cars adapted to actuate the jaws of the car for closing the same, and a locking member for locking said jaws over said link, the jaws of the other car being adapted to remain open under the action of the gravity.

3. A car coupling comprising a pair of pivoted jaws, a link or the like adapted to be engaged by the jaws, said jaws being operated by the contact of the link so as to engage the link, and means for locking the jaws in the closed position, said jaws tending to remain in an open position under the action of their own weight.

In testimony whereof I affix my signature in presence of two witnesses.

LUIGI OLIVERO.
